UNITED STATES PATENT OFFICE.

CORNELIUS CALLAHAN, OF BOSTON, MASSACHUSETTS, ASSIGNOR TO THE
CORNELIUS CALLAHAN COMPANY, OF SAME PLACE.

RELIEF-VALVE.

SPECIFICATION forming part of Letters Patent No. 445,041, dated January 20, 1891.

Application filed October 9, 1890. Serial No. 367,521. (No model.)

To all whom it may concern:

Be it known that I, CORNELIUS CALLAHAN, of Boston, in the county of Suffolk and State of Massachusetts, have invented certain new and useful Improvements in Relief-Valves for Gravity or Increased Water Pressure, of which the following is a specification.

My invention relates to relief-valves for gravity or increased water pressure—that is, to devices contrived to relieve the apparatus and hose of the back action of the water or pressure of the water above a predetermined degree.

It is the object of the invention to provide a relief-valve which shall be simple in construction, certain in its operation, and thoroughly efficient for the purposes for which it is intended.

The invention consists of the improvements in relief-valves which I will now proceed to describe and claim, reference being had to the annexed drawings, and to the letters of reference marked thereon, forming a part of this specification, the same letters designating the same parts or features, as the case may be, wherever they occur.

Of the aforesaid drawings, Figure 1 is a perspective view of a relief-valve casing equipped with my improvements. Fig. 2 is a vertical central sectional view thereof. Fig. 3 is a transverse vertical sectional view.

In the drawings, *a* designates a valve-casing adapted to be attached to a pump or hydrant, and constructed, as at *b*, so as that a hose may be coupled thereto, *c* designating an exit-port, through which the water may be led to a section of hose and conveyed back to the pump or be discharged upon the ground.

d designates a valve secured to the lower end of the valve-stem *e*, and held normally on its seat *f* to close the port *c* by means of a spring *g*, operating at its upper end against the lower face of the valve *h*, secured to the upper end of the valve-stem and at its lower end on the bottom of the valve-chamber *i*.

j designates ports leading from the chamber *k* of the valve-casing to the valve-chamber *i*, so that water may be admitted to said chamber *i* and operate against the valve *h*, the face of which is of greater area than the face of valve *d*, so as to overbalance the latter and

insure the retention of the valve *d* against its seat *f*, and thus keep the outlet-port *c* closed.

l designates a chamber formed in a projecting part *m* of the valve-casing *a*, in which chamber is arranged a valve *n*, adapted to be pressed against its seat *o* by means of a spring *p*, which operates against the rear face or end of the valve *n*.

r designates a port leading from the valve-chamber *l* down to a point below the valve *d*, so that if the valve *n* should be drawn back from its seat *o*, as represented in Fig. 2, the water in the chamber *i* might flow through the port *r* and be discharged through the port *c*.

The annular enlargement *m* on the valve-casing is screw-threaded on its exterior, as represented at *s*, and a screw-cap *t*, constructed so that it may be turned upon the enlargement or stem *m*, and thus regulate the degree of tension with which spring *p* may bear against valve *n* to hold the same upon its seat *o*.

u is a set-nut screwed upon the annular stem *m*, and adapted to be turned up against the inner end of the screw-cap *s* after the latter has been so adjusted as to cause the spring *p* to bear with the requisite stress upon the valve *n*, as before explained.

The operation of my improvement is as follows: Supposing that it is desired that the pressure of the water upon the hose or apparatus should not exceed one hundred pounds to the square inch, the screw-cap *t* will be turned up against the spring *p* to an extent that a fraction of pressure above one hundred pounds to the square inch would overcome the stress or tension of the spring and force the valve *n* back from its seat. With this adjustment of the parts the valves *d* and *h* will assume the positions in which they are represented in Fig. 3, water passing up into the chamber *i* and operating against the face of the valve *h* with greater force than it operates against the face of the valve *d*. Should the apparatus be in operation and the water shut off from the nozzle of the hose or from any other reason the pressure of the water should tend to exceed one hundred pounds to the square inch, this undue force operating against the valve *n* will force the same back from its seat against the stress of spring *p*, opening the

port *r*, and releasing the water in the chamber *i*, as shown in Fig. 2, so that instantly the pressure of the water upon valve *d* will become much greater than upon the valve *h*.
 5 As a consequence, the latter valve will be forced down from its seat, as represented in Fig. 2, opening the port *c* and allowing the water to flow or be forced out therethrough. The instant the pressure of water in the apparatus falls below one hundred pounds to the square inch the spring *p* will operate to force valve *n* back upon its seat *o*, and the pressure of water in chamber *i*, operating against valve *h*, will raise the same and with 10 it valve *d*, and so close the port *c*, as represented in Fig. 3.

The ready manner in which the spring *p* may be adjusted so as to bear with greater or less force upon the valve *n* is an important 15 feature of the invention.

The valve *d* is supported somewhat loosely on the lower end of the valve-stem *e*, and the hole formed through the said valve is packed by a headed screw *v*, tapped into the lower 20 end of the valve and clamping a washer *w* between the head of the screw and the surface of the valve surrounding said hole.

It is to be observed that the construction of the device is exceedingly simple, and that it 25 is certain of operation and not liable to get out of order.

It is obvious that changes may be made in the form and arrangement of parts comprising the improvements without departing from 30 the nature or spirit of the invention.

Having thus explained the nature of my invention and described a way of constructing and using the same, I declare that what 35 I claim is—

1. A relief-valve for gravity and increased water pressure, consisting of the valve-casing provided with an outlet-port *c* and valve-chamber *i*, a valve *h* in said chamber, ports *j*, leading from the casing-chamber to the valve-chamber *i*, a valve *d* to close the outlet-port *c*, a valve-stem connecting the two valves *d* *h*, the face of the valve *h* being of greater area than the face of the valve *d*, the valve-chamber *l*, the spring-pressed valve *n* to close the port leading from the valve-chamber *i* to the valve-chamber *l*, and a port or passage *r*, communicating between the valve-chamber *l* and the outlet-port *c*, as set forth.

2. A relief-valve for gravity and increased water pressure, consisting of the casing *a*, provided with the outlet-port *c* and valve-chamber *i*, a valve *h* in said valve-chamber, ports *j*, leading from the interior of the casing to the valve-chamber *i*, a valve to close the outlet-port, a valve-stem connecting the two valves *d* and *h*, the face of the latter valve being of greater area than the face of valve *d*, the valve-chamber *l*, the valve *n* to close the port leading from the valve-chamber *i* to the valve-chamber *l*, a spring to press the valve *n* upon its seat, a screw-cap for adjusting the tension with which the said spring may bear upon the valve *n*, and a port *r*, leading from the chamber *l* to the outlet-port *c*, as set forth.

In testimony whereof I have signed my name to this specification, in the presence of two subscribing witnesses, this 30th day of September, A. D. 1890.

CORNELIUS CALLAHAN.
